UNITED STATES PATENT OFFICE

FREDERICK I. JOHNSON, OF FITCHBURG, MASSACHUSETTS.

AUTOMATIC PISTOL.

967,928.

Specification of Letters Patent. Patented Aug. 23, 1910.

Application filed December 30, 1908. Serial No. 470,016.

To all whom it may concern:

Be it known that I, FREDERICK I. JOHNSON, a citizen of the United States, residing in Fitchburg, in the county of Worcester 5 and State of Massachusetts, have invented an Improvement in Automatic Pistols, of which the following description, in connection with the accompanying drawings, is a specification, like letters on the drawings 10 representing like parts.

The present invention relates to an automatic pistol, and is embodied in a pistol of that type in which the spent shell is ejected in response to the recoil, the hammer, however, 15 being operated by the trigger which cocks and releases it by a single movement.

In the construction embodying the invention, the breech block which contains the firing pin is thrown back by the recoil, the 20 said breech block being connected with an inertia member or recoil piece, which is contained in a chamber above and parallel to the barrel, the breech block and the inertia member being formed in a single piece. The 25 breech block normally lies over the magazine which is contained in the handle, and is thrown back by the recoil to expose the top of the magazine and allow a new cartridge to be forced up in front of the breech block 30 to take the place of the spent shell which is ejected through an opening in the side of the pistol. The new cartridge is then pushed into the barrel in front of the breech-block by the action of a spring which 35 acts on the recoil-piece to push it forward. The hammer, which is pivotally supported behind the breech block, is provided with a spring and is arranged to be operated by the trigger through the agency of a push 40 rod which extends from an abutment on the hammer forward to the trigger, the said trigger acting on said rod to push it back, thereby cocking the hammer, the connection between the push rod and the trigger then 45 being broken so as to allow the hammer to operate. The push rod is not connected with the hammer, so that in the recoil movement the hammer is free to move independently of any movement of the trigger or 50 push rod, and merely follows the breech-block in both directions.

Figure 1 is a side elevation, partly in section, of a pistol embodying the invention; Fig. 2 is a similar view showing the parts in 55 the position they will reach at the end of the recoil movement.

The breech block *a*, which contains the firing pin *a*² to fire the cartridge contained in the barrel *b* is directly connected with a recoil piece or inertia member *c* which is 60 located above the breech block and contained in a chamber *c*² above and parallel with the barrel. The said inertia member or recoil piece, as it will be called hereinafter, is 65 acted upon by a spring *c*³ located in an extension of the chamber behind the recoil piece, there being also an external finger piece *c*⁴ by which the recoil member and the breech block may be pulled back to allow the first cartridge to pass from the magazine 70 into the space in front of the breech block and thence into the barrel, when the breech-block is moved forward by the spring. The magazine *d* is located in the grip or handle *d*² directly below the breech block *a*, so that 75 when said breech block is drawn back by hand or forced back by the recoil, a space is afforded for the top cartridge which is then pushed forward into the barrel through the action of the spring *c*³ which restores the 80 recoil piece and breech block to their normal position. The hammer *e* is pivotally supported at *e*² below and at the rear of the breech block and is provided with an engaging portion *e*³ to be acted upon by a push 85 rod *f* which in turn is acted upon by the trigger *g*. The push rod *f* is not connected with the hammer, but is merely held by a suitable guideway in engagement with the portion *e*³, so that the hammer is free to be 90 moved back independently of said push rod in the recoil operation.

The trigger *g* is provided with a tripping member *g*² which engages the front end of the push rod *f*, so that when the trigger 95 is pulled, the said push rod is forced back throwing the hammer back into firing position, the final movement of the trigger disengaging the tripping member *g*² from the push rod *f*, thereby releasing the hammer to explode the cartridge.

The recoil of the explosion throws the shell back carrying with it the breech block *a* and the recoil piece *c* until the shell comes into line with a lateral opening through the frame of the pistol, (see Fig. 2,) and in its backward movement is acted upon by an ejecting member in the usual way. The spent shell is thus thrown out, leaving a space for the inclosed cartridge which is 105 pushed up by the spring in the magazine, and then forced forward into the barrel by 110

the forward movement of the recoil piece through the operation of the spring c^3 . The pistol is thus automatically loaded ready to be fired by the next movement of the trigger which cocks and releases the hammer.

5 Claims:

1. In an automatic pistol, the combination with the hammer; of the trigger; means whereby the trigger is caused to cock and release said hammer; a recoil-operated extracting and loading device consisting of a movable breech block having an offset extended portion, said breech block and said extended portion together constituting a recoil piece; a tubular guide-way for said extended portion parallel to the barrel; and a spring located in said guideway behind the extended portion.
- 10 2. In a pistol, the combination with the barrel; of a tubular guide-way located above

25 said barrel; a recoil piece comprising a breech block and an offset guide portion, said guide portion being located in a tubular guide way above the barrel, and the breech block extending downward therefrom into alinement with and behind the barrel; a spring operating directly on said guide portion; a pivotally supported hammer behind the breech block; a push rod acting on said hammer, but not connected therewith; 30 and a trigger to act upon said push rod to cock the hammer and release the push rod when the hammer has been cocked.

In testimony whereof, I have signed my name to this specification in the presence of 35 two subscribing witnesses.

FREDERICK I. JOHNSON.
